UNITED STATES PATENT OFFICE.

GEORG KARLO VILLY JÖRGENSEN, OF COPENHAGEN, DENMARK.

SOUND FUNNEL FOR RADIOTELEPHONY OR OTHER SOUND REPRODUCTION.

Application filed January 27, 1925, Serial No. 5,024, and in Denmark December 2, 1924.

- The invention relates to a sound-funnel for radio-telephony or other sound-reproduction. The distinguishing feature of the invention is that the sound-funnel is formed of two layers of wood with an interposed helically wound steel wire (piano wire) by means of which the parts composing the inner layer of wood are bound tightly together. Hereby the advantages are attained partly that the sound funnel is reinforced so as to become more solid and durable, partly that the reproduction of sound becomes exceedingly pure, clear and distinct and especially free of all disturbing secondary sounds.
- In the drawing accompanying and forming part of this specification—
- Fig. 1 shows the sound-funnel in side elevation with the outer layer of wood partly removed, and
- Fig. 2 a section along the line II—II in Fig. 1 to a larger scale.
- The sound-funnel is formed by an inner layer of thin strips *a*, for instance eight strips, in such a manner that the sound-funnel will be of octagonal cross-section. Bending of the wooden strips and gluing together of their edges is effected in known manner by use of a core corresponding to the shape of the sound-funnel desired. After bending and gluing of the inner layer of strips has been finished the funnel thus formed is wrapped with a steel wire (piano wire) *b*, the winding beginning at the narrow end of the funnel and being continued with one single unbroken wire laid helically with suitable pitch throughout the entire length of the funnel clear up to the funnel mouth. The steel wire is wound quite tightly about the funnel in such a manner that it cuts into the edges of the funnel, whereby it is held securely in position on the funnel. When the winding operation is finished, an outer layer of thin wooden strips *c*, suitably of the same thickness as the inner layer of strips *a*. The strips *c* are attached by gluing to the inner layer.
- Experiments have shown that the wrapping of fine steel wire about the inner funnel portion causes the sound reproduction to be far better than if no such wrapping were provided.
- The same manufacturing process may also be used in other fields where box-shaped, tubular or otherwise shaped wooden articles are produced.
- Having thus described my invention, what I claim is:—
1. Sound-funnel for radiotelephony and other sound reproduction, comprising an inner and an outer layer of wood, metal wire wrapped around said inner layer, and means for connecting said outer layer to the inner layer.
  2. Sound-funnel for radiotelephony and other sound reproduction, comprising an inner and an outer layer of wood, and metal wire wrapped around said inner layer, the outer layer being connected with the inner layer by means of glue.
- In testimony whereof I have signed my name to this specification.

GEORG KARLO VILLY JÖRGENSEN.
